ANTENNA COIL

James Shirey, 5259 Redding Drive, Zucky Lake,
Box 332, Brighton, Mich. 48116

Continuation of abandoned design application Ser. No.
73,649, Feb. 20, 1963. This application June 18, 1964,
Ser. No. 80,543

Term of patent 14 years

(Cl. D26—14)

FIGURE 1 is a side view of an antenna coil embodying my new design;

FIGURE 2 is a view at one end thereof; and

FIGURE 3 is a view of the other end thereof; the non-visible sides are substantially identical to the one shown.

This application is a continuation of my co-pending companion application, Serial No. D-73,649, filed February 20, 1963, now abandoned.

I claim:

The ornamental design for an antenna coil, as shown and described.
